UNITED STATES PATENT OFFICE.

VICTOR G. VAUGHAN, OF WILKINSBURG, PENNSYLVANIA, ASSIGNOR TO WESTINGHOUSE ELECTRIC & MANUFACTURING COMPANY, A CORPORATION OF PENNSYLVANIA.

HEATER-BRICK TERMINAL.

Application filed July 20, 1923. Serial No. 652,663.

To all whom it may concern:

Be it known that I, VICTOR G. VAUGHAN, a citizen of the United States, and a resident of Wilkinsburg, in the county of Allegheny 5 and State of Pennsylvania, have invented a new and useful Improvement in Heater-Brick Terminals, of which the following is a specification.

My invention relates to electric heating 10 devices and particularly to electric heating units.

The object of my invention is to provide a relatively simple and efficient terminal structure for an electric heating unit.

15 Patent No. 1,424,290, to F. F. Forshee, discloses a heater brick for an electric range in which the same member serves to hold the inner end of the terminal bars against the refractory plate and also to hold the ends 20 of a resistor member against the terminal bars. This construction does not permit of the terminal bars adjusting themselves to the co-operating terminal members in case of any misalignment of the latter. It 25 is also very hard to determine whether the ends of the resistor wire are clamped tightly, as they are usually located underneath the inner ends of the terminal bars.

Accordingly, the main object of my invention 30 is to provide a construction for an electric heating unit wherein the mounting of the terminal bars against the refractory heater support shall be independent of the means for electrically connecting the ends 35 of the resistor member to the terminal bars.

In practicing my invention, I provide a 40 plate of refractory electric-insulating material having a resistor member located in one surface thereof. A plurality of flat elongated terminal bars are loosely held adjacent to the other surface of the plate in parallel spaced relation relatively thereto and the end portions of the resistor member are secured to the terminal bars intermediate 45 the ends thereof.

In the single sheet of drawings,

Figure 1 is a bottom plan view of an electric heating unit embodying my invention, and

50 Fig. 2 is a view thereof, in side elevation, with a portion cut away to show the mounting of the inner terminal-supporting means.

An electric heating unit 11 comprises a flat disk 12 of a suitable refractory electric-insulating material that may be provided

with a groove in one surface thereof within which a resistor member 13 is located. As this part of the construction forms no part of my invention, it is not illustrated or described further in detail.

60 A plurality of terminal bars 14, 15 and 16 are located in parallel spaced relation adjacent to one of the surfaces of the plate 12 and as here shown are located adjacent to the bottom surface thereof. The bar 15 65 is substantially straight and extends from the center of the plate 12 to a short distance beyond the outer periphery on a radial line thereof. The two bars 14 and 16 are of angular form and have their inner ends located adjacent to the periphery of the plate 12 and their outer ends extend substantially parallel to the outer end of the bar 15.

70 The outer ends of the terminal bars are located in, and extend through, suitable 75 openings 17 in a terminal member 18 of the type described and claimed in the hereinbefore mentioned Forshee patent. The member 18 is secured against the under surface of the plate by a single metal member 80 19, of substantially U-shape, the outer ends of which are held by suitable bolts 21 and co-operating nuts 22. The inner ends of the bars 14, 15 and 16 are provided with a circularly curved end portion 23 within which 85 is located an elongated rivet member 24 that extends through suitable countersunk openings 25 in the plate 12. An annular washer member 26 is provided on the rivet member 24 intermediate its ends and located adjacent to or against, the under surface of the plate 12 in order to space the bars 14 from the under surface of the plate.

90 A cotter pin 27 is provided at the outer end of each of the rivets 24 in order to 95 loosely hold the inner end of the respective bars 14, 15 and 16 on the end of the rivet member 24.

100 The ends of the resistor member 13 extend through suitable openings 28 in the plate 12 and are secured against the terminal bars by means of short machine screws 29 and co-operating nuts 31, a spring washer member 32 being provided under the head of the machine screw 29 to assist in tightly clamping the end of the wire 13 against the flat surface of the bars intermediate their ends.

105 The openings 17 in the member 18 are made somewhat larger than the bars in order that these may fit loosely therein. As 110

hereinbefore noted, the rivet member 24 is loosely mounted in the plate 12 and the circularly curved portion 23 also fits loosely around the rivet member 24. As the outer 5 ends of the terminal bars are intended to operatively engage with resilient terminal members, not shown, that are mounted in a supporting structure for the heating unit 11, this loose mounting of the terminal bars 10 permits of adapting the same to any irregularities in the position of the terminal members or any misalignment thereof.

As a heating unit of this type is necessarily subjected to repeated heating and 15 cooling, during the normal operation thereof, any loosening effect of the nut 31 on the bolt 29 is entirely independent of the means for holding the inner end of the respective terminal bars in their proper operative 20 positions relatively to the plate 12.

I have found it relatively easy to maintain the operative engagement between the end of the resistor wire 13 and the terminal bars in a tight combination with this construction which was impossible when the same machine screw or elongated rivet 24 was employed for purposes of holding the end of the bar in its proper operative position relatively to the plate and also for securing the ends of the resistor member 30 against the ends of the bars.

Various modifications and changes may be made in the invention without departing from the spirit and scope thereof, and I desire that only such limitations shall be placed 35 thereon as are imposed by the prior art or set forth in the appended claims.

I claim as my invention:

1. A heating unit comprising a refractory

support, a resistor located in one surface 40 thereof, a plurality of rods extending through said refractory support, a plurality of flat terminal bars having one end loosely supported by said rods, and means for electrically connecting said resistor wire to said 45 terminal bars adjacent to the supporting rods.

2. A heating unit comprising a refractory plate, a resistor located in one surface thereof, a plurality of metal rods extending 50 through said plate in spaced relation, a plurality of flat terminal bars located adjacent to the other surface of said plate and each having one end loosely secured on and supported by one of said rods, and means for 55 securing end portions of said resistor to said bars adjacent to the supporting rods.

3. A heating unit comprising a refractory plate, a resistor located in one side of said plate, a plurality of terminal bars located 60 adjacent to the other side of said plate, means for loosely supporting one end of said bars from said plate, and means for connecting integral portions of said resistor member to said terminal bars intermediate 65 the ends thereof.

4. In a heating unit, in combination, a refractory plate, a resistor located in one surface of said plate, a plurality of terminal bars loosely held in substantially parallel- 70 spaced relation to the other surface of said plate, and means for securing end portions of said resistor to said bars intermediate their ends.

In testimony whereof, I have hereunto 75 subscribed my name this 11th day of July, 1923.

VICTOR G. VAUGHAN.
